1

This invention relates to a process for preparing valuable hydrocarbon products from a wax bearing high boiling mineral oil stock. It is particularly concerned with a process for obtaining from waxy stocks a substantially deoiled wax, gasoline and other products boiling lower than the original charge stock.

The present process is broadly applicable to the problem of separating wax and/or petrolatum and the like from hydrocarbon oils in substantially oil free form. The present process is particularly directed to the deoiling of crystallizable wax present in high waxy stocks such as in slack wax.

A process commonly employed heretofore for the deoiling of wax is the well known sweating process wherein the slack wax is chilled in pans to cause congealing of the wax after which the mass is slowly heated to effect sweating out of the liquid oil. The efficiency of this process is low as compared with other methods from the standpoint of wax yields. Moreover, the process is conducted batchwise and requires a considerable length of time and delicate temperature control during the heating period.

Another process employed is the solvent deoiling process in which the slack wax is mixed with a suitable solvent such as propane or benzol-acetone, for example, and then chilled and filtered.

Still another process currently employed in the emulsion deoiling process in which the slack wax is mixed with a nonviscous non-solvent while in molten state after which it is cooled to congeal the wax. Then the congealed wax is separated from the oil in non-solvent emulsion by means of a basket type centrifuge lined with a filter material. Such processes involve extensive wax recycle to obtain high yield of low oil content wax.

It has also been customary in the prior art to employ filter aids such as diatomaceous earth in powdered form to act as an air in the dewaxing of oils by the filtration of the wax from the liquid oil. In such a process the liquid oil from which most of the wax has been crystallized is withdrawn free of the filter aid and the waxy material. The process has not been found practicable as a method for deoiling waxes to obtain oil free wax. As a matter of fact, the waxy material left behind with the filter aid is generally known as slack wax and contains substantial amounts of oil.

In United States Patent 1,278,023, dated September 3, 1918, there is disclosed a process for dewaxing of oils wherein the waxy oil stock is

2

wholly absorbed by a solid porous material such as fuller's earth after which the fuller's earth is chilled to effect congealing of the sorbed wax. The fuller's earth is then treated with a suitable oil solvent whereby the liquid oil is removed leaving behind the wax within the pores of the adsorbent. The wax is subsequently separated from the solid adsorbent. This process is unsatisfactory because of the difficulty in obtaining satisfactory wax yields thereby and the difficulty of removing this wax from the adsorbent pores without the use of a second solvent for the wax. All of these processes provide as products only a deoiled wax and a foots oil fraction containing varying amounts of residual waxy material.

A major object of this invention is the provision of a process for separation of wax from oils which not only overcomes the disadvantages of the prior art processes described above but also provides a gasoline containing product instead of foots oil.

A specific object of this invention is the provision of a novel continuous, cyclic process for the deoiling of waxy stocks and the conversion of the oil removed to gasoline containing products by means of a porous solid adsorbent material.

These and other objects of this invention will become apparent in the course of the following discussion.

The present invention broadly comprises a process wherein the waxy stock such as slack wax is brought into intimate contact with a suitable porous particle form solid adsorbent material which is preferably catalytic in nature as to hydrocarbon cracking reactions. The temperature conditions of the contacting are controlled so that the waxy constituents of the charge stock become congealed in point of time at least substantially immediately after the initial contacting with the adsorbent whereby the waxy constituents become and remain coated on the outer surface of the adsorbent particles while the non-congealed liquid oil constituents are sorbed into the pores of the adsorbent. Thereafter the wax is removed from the surface of the adsorbent leaving behind the adsorbent bearing in its pores the sorbed oily constituents. The adsorbent is then heated to a temperature at which the oily constituents are cracked into lower boiling products which may be removed in the gaseous phase. The adsorbent may then be subjected to a regeneration wherein carbonaceous contaminants deposited during the cracking step are burned off by an oxygen containing gas. Thereafter

the adsorbent may be cooled and employed again for deoiling waxy stocks.

In order to obtain the optimum yields of wax it is highly important in this process that the temperature be controlled such that the waxy constituents in the waxy stock are in a congealed or crystallized state either prior to or preferably substantially immediately after being brought into contact with the solid adsorbent particles and remain congealed at least until the step of removing the wax from the adsorbent commences. It will be readily understood by those skilled in the art that such expressions as "congealed wax constituents" and "non-congealed liquid oil constituents" and the like as used in describing and claiming this invention do not necessarily mean pure oil-free wax or pure wax-free oil since the amount of wax which will congeal from a wax-oil mixture is to some extent dependent upon the temperature of the mixture. For example, if the mixture were cooled to 90° F. waxy constituents might congeal but in the non-congealed liquid oil there very probably will be present in non-congealed state some material which chemically should be classified as a wax. For the purposes of describing and claiming this invention a wax which is free of oil shall be taken as meaning one in which the oil content is zero as determined by the A. S. T. M. method for determining oil contents of waxy stocks, A. S. T. M. test number D721-43T.

The invention may be more readily understood by reference to the drawings attached hereto in which Figure 1 is an elevational flow plan, partially in section, of a preferred form of the invention and Figures 2 and 3 are detailed elevational views, partially in section, of certain portions of the system shown in Figure 1.

Turning now to Figure 1 and considering the invention from the standpoint of its operation, a suitable waxy charge stock such as slack wax entering through pipe 9 is pumped by pump 10 through heat exchanger 11 wherein it is heated to a temperature slightly above that at which the waxy constituents begin to congeal. The heated slack wax then passes via pipe 13 into the upper section of the elongated vertical vessel 14. The operation within vessel 14 may be more readily understood by reference together with Figure 1 to Figure 2 which shows in more detail the construction of tower 14. A column of the molten slack wax is maintained within section A of the coating tower 14. A column of water or other suitable cooling liquid is maintained within a lower section of tower 14. This liquid should be of greater density than the slack wax and a non-solvent as to both wax and oil. The water in that portion of the tower 14 just below the slack wax column is maintained at a temperature sufficiently high to avoid congealing of wax at the interface between the slack wax and water columns. This is accomplished by circulating water through pipe 17 into and through heat exchanger 18 and back into the water column via pipe 19 just below the interface. Cold water enters the water column via pipe 20 below the level of warm water outlet pipe 17. Particle form porous adsorbent material which may preferably be of spherical form enters the tower 14 from supply hopper 110 via vertical pipe 21 at about the same temperature as the slack wax or at a somewhat lower temperature. In general, the inlet temperature of the adsorbent should usually be below about 100° F. and preferably below about 80° F. The rate of introduction of adsorbent is controlled by adjustment of the height of the outlet end of pipe 21 from

conical spreader 22 and by rotation of spreader 22. The spreader is rotated by means of gears 23, shaft 24 and motor 40. Upright conical baffles 25 and 26 supported by rods 27 and 28 are properly positioned below the spreader 22 in such a manner as to distribute the particles of adsorbent uniformly over the entire cross-section of the tower 14. The adsorbent particles drop downwardly through the column of slack wax and become coated on their surface with a film of slack wax. The particles then drop into the water column and the cool water acts to congeal the wax constituents on the surface of the particles. When the difference between the particle density and cooling liquid is small, it is desirable to add some substance such as potassium oleate to the water or other cooling liquid to lower the interfacial tension at the water-slack-wax interface. This will prevent hold up of adsorbent particles at this interface. The particles of adsorbent bearing the congealed material on the surface thereof settle to the bottom of tower 14 and are picked up by the continuous bucket elevator 29 which connects into the lower section of tower 14. The buckets 31 are 15 perforated on their bottoms so that the water may drain from the adsorbent in the buckets once the buckets rise above the level of the liquid column in the elevator shaft. The partially drained adsorbent is discharged from elevator 29 through 20 duct 30 onto a moving screen belt drainer 32 driven by motor 34. A drainer of this type is shown in attached Figure 3 at 70 and will be described hereinafter. The separated water is withdrawn from the drainer 32 through pipe 36 to 25 accumulator 61. The water may be cooled in accumulator 61 by means of a cooling fluid passing through coil 32. Cold make up water may be introduced into the accumulator 61 through pipe 64. The water passes from accumulator 61 via 30 pipe 35, pump 33 and pipe 20 back to the coating 35 tower 14. The drained adsorbent material coated with the waxy stock is discharged from drainer 32 into conveyor 37. The adsorbent is discharged from conveyor 37 into one of the sorption tanks 38 or 38'. These tanks are several in 40 number although only two are shown. The tanks are employed in cycle, each tank being shut off from the conveyor after being filled with adsorbent to the desired level. The adsorbent is 45 permitted to stand in the sorption tank while the temperature is controlled by means of heat transfer tubes (not shown) at a level at which the wax constituents of the slack wax will remain congealed. A suitable cooling fluid may be supplied 50 to the heat transfer tubes within each of the tanks 38 via pipe 41 and withdrawn via pipe 42. The adsorbent is retained within the tank 38 or 38' until substantially all of the non-congealed liquid oil constituents of the slack wax are sorbed 55 from the congealed mass on the surface of the particles into the pores of the particles leaving substantially only the waxy constituents coated on the outer surface of the adsorbent particles. The adsorbent is then withdrawn through outlets 39 and 39' and conveyed by screw conveyors 43 and 44 into the upper section of the wax melting tower 45 which is maintained substantially 60 filled with a column of hot water. The operation of the wax melting tank 45 may be more readily 65 understood by reference to Figure 3 in conjunction with Figure 1. In Figure 3 there is shown in greater detail the wax melting tank 45 and the subsequent drainer 70 and wax separating tank 49. The adsorbent particles drop from conveyor 70 70 through the column of hot water in a zig zag

path provided by baffles 46 so that the wax deposited on the surface of the particles is melted off from the particles and is passed from the upper section of tower 45 via pipe 48 to the wax separator 49. The molten wax is withdrawn from the upper section of separator 49 via pipe 50 and the separated water is returned via pipe 109, pump 51 and pipe 52 to the lower section of the wax melting tower 45. The water is maintained substantially above the melting point of the wax by means of the heating coil 53 within separator 49. The adsorbent particles which still retain the liquid oil within the pores of the particles are carried from the bottom of tower 45 in a water stream via conduit 54 and discharged onto the moving screen drainer 66. The screen 66 is a continuous screen which passes over rollers 112 and 113, the roller 113 being driven by motor 114 through belt 115. The screen 66 is of such mesh size as to permit passage of water therethrough while retaining the adsorbent particles. A pan 67 is provided to catch the water passing through the screen. This water passes via pipe 68 into accumulator 49 from which it is returned via pipe 109, pump 51 and pipe 52 to the melting tank 45. Additional warm make up water is added to the accumulator through pipe 78'. The drained adsorbent material passes from the end of moving screen 66 into duct 71 by which it is delivered into a purging apparatus 120 which may be a moving screen similar to that shown in chamber 70, which screen is driven by motor 121. A suitable purge gas such as steam or heated flue gas may be introduced via pipe 122 and caused to jet down on the adsorbent on the moving screen so as to purge additional water from the catalyst. The purge gas may be withdrawn from the purging apparatus via pipe 123 while the water removed from the adsorbent passes via pipe 124, pump 125 and pipe 126 to pipe 68 leading to accumulator 49. The purged catalyst drops through duct 127 into conveyor 128 by which it is transferred to a cracking reactor supply hopper 129. The adsorbent bearing the oily constituents then passes downwardly through gravity feed leg 130, seal zone 131 and pipe 132 into the reactor 133 wherein it is mixed with hot regenerated adsorbent of similar type in such proportions as to provide a mixture temperature suitable for converting the sorbent oily constituents to lower boiling gasoline products. The hot regenerated adsorbent is obtained from hopper 137 from which it flows via gravity feed leg 138 into seal zone 140 and then via pipe 139 into reactor 133. An inert gaseous blanket, for example of flue gas or steam, is maintained in seal zones 131 and 140 to prevent escape of hydrocarbon gases through feed legs 138 and 139. The converted hydrocarbon products are withdrawn in gaseous phase from the lower section of the compact adsorbent column in reactor 133 via pipe 141, and may be fractionated in conventional equipment. The spent adsorbent now substantially free of oily constituents but bearing a carbonaceous contaminant deposit, is purged free of hydrocarbon gases by means of an inert purge gas, for example steam or flue gas, entering at 142 and is then passed from the reactor via pipe 143 to conveyor 144. The adsorbent is transferred by conveyor 144 to regenerator 145 in which it is contacted with air introduced at 146 to burn off the contaminant deposit. The combustion products are withdrawn from regenerator 145 via pipe 147. The temperature of the adsorbent may be controlled below a heat damaging level during re-

generation by means of a cooling fluid passed through heat transfer tubes (not shown) within the regenerator. The heat transfer medium may be supplied to the tubes via conduit 148 and withdrawn therefrom via conduit 149. In general clay type adsorbents should be controlled below about 1200° F. and synthetic gel type adsorbents below about 1400° F. during regeneration to prevent permanent loss in activity. The regenerated adsorbent is passed from the lower end of the regenerator 145 via pipe 150. A portion of the hot regenerated adsorbent passes to conveyor 151 by which it is transferred to the reactor supply hopper 137. The remaining portion of the regenerated adsorbent passes via pipe 153 to conveyor 158 by which it is transferred to the cooler-hopper 110. In hopper 110 the adsorbent is cooled to a temperature suitable for its reuse in the coating tower 14. In general, the adsorbent should be cooled to a level below about 100° F. and preferably below about 80° F. The cooling may be accomplished by introducing a cold gas into the bed of adsorbent in the cooler via pipe 155 and passing the gas through the bed. The gas may be withdrawn from the cooler through pipe 156. The cooled adsorbent then passes via pipe 21 to the coating tower 14.

The conversion system shown is of the continuous type wherein the adsorbent, preferably a cracking catalyst, moves through the reactor and regenerator chambers as a compact column of particles. The operating conditions within the reactor 133 will vary depending upon the activity of the catalyst employed (if it is a catalyst) the particular characteristics of the oily constituents sorbed on the cool adsorbent charge, the reaction involved and the products desired. In general, it has been found desirable to maintain the pressures within a range varying from below atmospheric to about 200 pounds per square inch. Pressures of the order of 5 to 50 pounds per square inch gauge are preferred. The temperature for the conversion for cracking operations may vary from about 800° F. to 1100° F., temperatures of the order of 850° F. to 1000° F. being preferred where gasoline is the desired product. Where non-condensable gases are the principal desired product somewhat higher temperatures may be employed. The ratio of contact material to hydrocarbon throughput for the reactor may vary from about 1.0 to 40 parts by weight of adsorbent per part of hydrocarbon charge. The ratio of fresh hot regenerated adsorbent introduced via pipe 139 to cooler adsorbent, bearing sorbed oily constituents, introduced via pipe 132 should be so controlled that the resulting temperature of the mixture is suitable for accomplishing the desired hydrocarbon conversion. The exact ratio used may be varied somewhat by control of the temperature of the hot regenerated adsorbent and by preheating the oil bearing adsorbent before its introduction into the reactor 133. It has been found preferable to employ about 2 to 10 parts by weight of fresh hot regenerated adsorbent per part of the cooler adsorbent bearing the oily constituents.

In some operations it may be desirable to add additional liquid or vaporized hydrocarbon charge into the reactor 133 via conduit 160 to be cracked concurrently with the oily constituents on the adsorbent from hopper 129. The mixed conversion products are withdrawn together via conduit 141.

While the above described arrangement for converting the oily constituents to lower boiling

products represents a preferred form of this invention, the invention is not considered to be limited thereto. The conversion reaction may be strongly catalytic or mostly pyrolytic depending on the nature of the particular adsorbent employed. Moreover, the adsorbent may be heated to the conversion temperature by means other than that described above. For example, it may be heated by mixing with a hot inert heat carrying material which may be later separated from the regenerated adsorbent. Also the adsorbent may be heated by means of a suitable heat exchange fluid passed either in direct or indirect heat transfer relationship with the adsorbent particles. The adsorbent may be heated by partial oxidation and burning of the oily constituents thereon. The adsorbent may pass through the reaction zone as a compact stream, a stream of suspended particles or as a fluidized bed. On the other hand the adsorbent may be charged to a suitable vessel wherein it remains in place during the heating, hydrocarbon conversion and adsorbent regeneration steps. In some operations wherein the reaction is more pyrolytic than catalytic and wherein the amount of carbonaceous contaminant deposited on the adsorbent is small, the adsorbent may be cooled and reused in the coating tower without regeneration after each reaction step. When after a number of cycles a substantial contaminant deposit has accumulated, it may then be removed by burning. All of these and other modifications which will be apparent to those skilled in the art are considered to be within the broad scope of this invention.

The invention is also not to be considered as limited to the particular method for coating the adsorbent with waxy stock and for recovering the deoiled wax described hereinabove. In an alternative method instead of effecting the congealing of the wax after contact with the adsorbent, the waxy constituents of the charge stock may be caused to congeal at least partially so as to provide a soft pasty mass into which particles of adsorbent are pressed. Then after the mass has been maintained in congealed state for sufficient time for sorption of the oily constituents into the pores of the particles, the wax may be melted to separate from adsorbent particles. This and other methods for coating the waxy stock on the adsorbent are shown and broadly claimed in copending application Serial Number 31,948, filed in the United States Patent Office June 9, 1948, in which one of the present applicants is applicant. Any of the methods described in that application may be employed in the process of this invention.

It will be readily understood that apparatus and methods other than that shown in Figure 1 may be employed to accomplish the transfer of materials between vessels, the adsorption step and the draining and wax melting and oil recovery steps. Moreover, the removal of wax from the surface of the adsorbent particles may be accomplished by methods other than by the melting of the wax. For example, the wax may be removed from the particles while in solid form by mechanical attrition. This latter method is particularly applicable when the wax is of brittle texture and where the adsorbent particles are spherical in form. One method for accomplishing the mechanical separation is to rotate the adsorbent particles in a closed drum for a period of time to crack off the brittle wax. The particles of wax may then be separated from the adsorbent particles by elutriation, i. e. suspension in a

stream of gas the flow rate of which is controlled to carry off the wax particles without entraining the adsorbent.

A wide variety of adsorbent materials may be employed in the process of this invention. For example, bauxites, fuller's earth, synthetic silica, alumina or silica and alumina gel catalysts and other materials of similar porosity. Certain porous sorptive silica glasses such as are described in United States Patent 2,106,744, issued February 1, 1938, to Hood et al. may be employed. In general, the pore size of the adsorbent material should be adapted to effect rapid sorption thereinto of the oily constituents of the waxy charge stock. The adsorbent particles should be of substantial size as distinguished from powdered adsorbents. When powdered adsorbents of size less than about 100 mesh Tyler are employed the waxy constituents tend to be sorbed into the pores along with the oily material before complete congealing of the waxy constituents can be accomplished thereby preventing the desired separation. In general, it has been found that the adsorbent particles should be broadly at least about 0.01 inch and preferably at least about 0.022 inch and less than about 0.5 inch average diameter. A preferred adsorbent is a synthetic silica-alumina gel catalyst in spherical form prepared in the manner described in U. S. Patent 2,384,946, issued September 18, 1945, to Milton M. Marisic.

In conducting the methods described in connection with Figures 1, 2 and 3, the temperature of the waxy stock as brought into initial contact with the adsorbent should be only several degrees above that at which the waxy constituents will commence to congeal. The temperature of the cooling fluid employed to cause the congealing of wax constituents and to maintain them congealed during the sorption period will, of course, vary somewhat depending on the melting point of the waxy constituents involved. For many operations a cooling water temperature of about 70° F. has been found satisfactory. The operation should be conducted so as to effect congealing of the waxy constituents as soon as possible after the initial contacting with the adsorbent. The waxy constituents should be congealed at least within about 10 minutes of the initial contacting and preferably within less than one minute thereof.

The ratio of adsorbent to waxy charge stock employed will depend to some extent upon the oil sorption capacity of the adsorbent, the percentage of oil present in the waxy stock and other operating variables. In general, for synthetic gel catalysts the ratio should be of the order of 0.5 to 10 pounds of adsorbent per pound of waxy stock. In any case, sufficient adsorbent should be employed to sorb substantially all of the oily constituents in the waxy charge.

The length of time to be devoted to the sorption period during which non-congealed liquid constituents are sorbed into the pores of the adsorbent will vary depending upon the thickness of the waxy stock coating on the adsorbent particles and upon the particular adsorbent involved and the viscosity and molecular size of the oily constituents under the sorption temperature conditions required to maintain the waxy constituents in a congealed state. In general, it has been found that with adsorbent particles of about 0.09 to 0.19 inch average diameter and having a porosity similar to a synthetic silica-alumina gel catalyst the length of the sorption period should

be at least about 0.1 hour and preferably from 1 to 24 hours.

In general the average thickness of the waxy stock coating around each adsorbent particle should be less than about 0.1 inch and preferably less than about 0.05 inch.

As an example of the process of this invention the production of a deoiled waxy product and of a gasoline containing product from a waxy mineral oil stock by the general method shown in Figure 1 may be considered. The waxy charge stock was a paraffinic petroleum stock having a melting point of 116.9° F. as determined by the test procedure recommended by The American Society for Testing Materials, test number A. S. T. M. D-87-42 and an oil content of 19.2 as determined by A. S. T. M. tentative test number D-721-43T. The adsorbent employed was a synthetic silica-alumina gel bead catalyst prepared by the method described in United States Patent 2,384,946, dated September 18, 1945. The catalyst had a bulk density of about .74 as determined by pouring the catalyst into a measured container and weighing. The individual particle density was about 1.15. The catalyst particle size was about 0.09 to 0.19 inch average diameter. The catalyst beads were dropped through a column of molten waxy stock one inch in depth and maintained at about 126 to 133° F. The weight ratio of catalyst to waxy stock charge was about 3.5 to 1. The catalyst beads bearing a coating of waxy stock then dropped through a column of cooling water maintained at about 70° F. About 0.3 to 0.5% potassium oleate was added to the water to reduce the interfacial tension at the water wax interface. The catalyst bearing the congealed coating of waxy stock was permitted to stand for about four hours at about 80° F. after which the wax remaining on the surface of the particles was removed by mechanical attrition. The recovered wax had a melting point of 125.3° F. and an oil content of 3.2% by weight and the yield of recovered wax amounted to 58% by weight based on the waxy stock charge or 72% by weight of the wax present in the charge as determined by A. S. T. M. test method D-721-43T. By way of a comparison the yield of wax obtained by the method described above using a minimum cooling water temperature of 70° F. amounted to 83% by weight of the yield of wax obtained by solvent deoiling the same waxy stock employing benzol-methyl ethyl ketone as the solvent at a temperature of 0° F. The wax obtained by the solvent deoiling process contained 2.4% by weight oil. The adsorbent substantially freed of waxy constituents contains about 12% by weight of an oily paraffinic stock somewhat similar to foots oil although containing less waxy material and may be purged substantially free of water and mixed at about 100° F. with about 2.5 to 3.0 times its weight of hot regenerated catalyst entering the reaction zone at about 1100° F. whereby it is heated to a suitable hydrocarbon conversion temperature. A heated gas oil charge entering at about 850° F. may be passed through the catalyst charge in amount controlled to provide an overall catalyst to hydrocarbon oil charge ratio of about 2 parts catalyst to one part total oil charge to the reactor. The reaction pressure is about 5 pounds per square inch gauge. Gasoline containing hydrocarbon products may be withdrawn in gaseous phase from the reactor and the spent catalyst may be separately withdrawn at about 800° F. The spent catalyst is regenerated by burning the

contaminant and a portion of the regenerated catalyst is cooled to about 80° F. and recycled to the coating tower.

In another experiment conducted similarly to the one just described the sorption period was increased from 4 to 20 hours and the catalyst to waxy oil charge ratio to the coating tower was decreased from 3.5 to about 1.4. The wax yield was increased to 61% by weight of the original waxy charge stock but the oil content in the recovered wax increased to about 6.7% of the wax. The catalyst after removal of wax from its surface contained about 28% by weight of oily paraffinic material. This amounted to a catalyst to oil ratio of about 3.5 to one by weight which is a satisfactory ratio without addition of extraneous oil charge or catalyst in the cracking step. Thus, the catalyst may be heated alone to about 850° F. by means of a heat exchange fluid to crack off the sorbed oily constituents.

It should be understood that the specific details of operation and of apparatus arrangement and the specific modifications of this invention given hereinabove are intended as exemplary and the invention is not to be construed as being limited thereto or otherwise limited except as limited by the following claims.

We claim:

1. The method of obtaining a deoiled waxy product and a gasoline containing product from a wax bearing high boiling mineral oil which comprises: subjecting the wax bearing oil to an intimate contacting with a suitable particle form solid adsorbent material of at least 0.01 inch average diameter, maintaining the temperature during at least most of said contacting at a level at which wax constituents of said wax bearing oil are congealed beginning at a time falling within the period of prior to the initial contacting to substantially immediately after the initial contacting of the liquid with the adsorbent, whereby the congealed wax constituents remain deposited on the surface of said adsorbent and the non-congealed liquid constituents are sorbed into the pores of said adsorbent, thereafter removing the wax constituents from the surface of said adsorbent while leaving the non-congealed liquid constituents within the pores of said adsorbent, heating the adsorbent containing said liquid constituents in the absence of said removed wax constituents to a temperature at which said liquid constituents are converted to a lower boiling gasoline containing product and separating said product from the adsorbent.

2. A cyclic process for removing oily constituents from a waxy hydrocarbon stock which comprises: subjecting said waxy stock to an intimate contacting with a particle form solid adsorbent material made up of particles having an average diameter within the range about 0.022 to 0.5 inch, maintaining the temperature of the waxy stock during at least most of said contacting at a level at which waxy constituents of said stock are precipitated beginning at a time falling within the period of any time prior to the initial contacting to not more than 10 minutes after the initial contacting of the liquid with the adsorbent, whereby the non-precipitated liquid constituents are sorbed into the pores of said adsorbent while the precipitated waxy constituents remain deposited on the outer surface of the adsorbent particles, thereafter effecting removal of said precipitated waxy constituents from said adsorbent leaving the oily constituents sorbed in the pores of the adsorbent particles, heating the adsorbent in the

absence of said removed waxy constituents to a temperature at which said oily constituents are converted to lower boiling hydrocarbon products, withdrawing said lower boiling products in the gaseous phase from the solid adsorbent, cooling the adsorbent particles and again contacting them with waxy stock as aforesaid.

3. The method of preparing a gasoline containing product and deoiled wax from a waxy mineral oil stock which comprises: subjecting said waxy stock to an intimate contacting with particle form solid adsorbent material having an average particle diameter of at least 0.01 inch, maintaining said waxy stock in contact with said adsorbent for a period of at least 0.1 hour, under conditions at which at least most of the waxy constituents in said waxy stock are congealed whereby the non-congealed liquid constituents of said waxy stock are sorbed into the pores of said adsorbent particles while the congealed waxy constituents are left deposited upon the surface of said adsorbent particles, effecting removal of the congealed waxy constituents from said adsorbent particles in a separate zone while leaving substantially all of said liquid constituents still sorbed in the particle pores, heating the adsorbent particles in the absence of the separated waxy constituents to a temperature suitable for conversion of said sorbed liquid constituents to a lower boiling gasoline containing product, separating the gasoline containing product in gaseous phase from the solid adsorbent, cooling the adsorbent to a temperature suitable for contacting the waxy charge stock as aforesaid and again contacting it with a waxy charge stock.

4. A cyclic process for converting a high boiling waxy mineral oil stock to deoiled wax and gasoline containing products which comprises: intimately contacting the waxy oil stock with a particle form solid adsorbent material suitable for use as a hydrocarbon cracking catalyst, said material consisting principally of particles of at least 0.01 inch average diameter, substantially excluding the sorption of the waxy constituents in said mineral oil stock into the pores of said adsorbent particles by maintaining said waxy constituents in congealed form while permitting the non-congealed liquid constituents to be sorbed into the pores of said adsorbent, and after substantially all of said liquid constituents are sorbed in the pores of said adsorbent effecting a separation of the adsorbent bearing said liquid constituents from said waxy constituents in a separate zone, heating the catalyst in the absence of the separated waxy constituents to a temperature suitable for effecting conversion of said sorbed liquid constituents to lower boiling gasoline containing products, maintaining said catalyst at the suitable conversion temperature to effect said conversion with a resultant deposition of carbonaceous contaminant on said catalyst, separating the gasoline containing products in the gaseous phase from said solid catalyst, subjecting the used catalyst to contact with air to effect removal of said contaminant by burning at a controlled elevated temperature, cooling the catalyst and again employing it for contacting waxy mineral oil stock as aforesaid.

5. The method of separating oily constituents from waxy constituents present in a waxy hydrocarbon stock which comprises: coating said waxy stock onto the surface of particles of solid adsorbent material of greater than about 0.01 inch average diameter, permitting the adsorbent particles to remain coated with said waxy stock for

a period within the range 0.1 to 24 hours and maintaining the temperature of the waxy stock during substantially said entire period beginning at least substantially immediately after initial contact with said adsorbent at a level at which waxy constituents in said stock are congealed whereby the non-congealed liquid constituents are sorbed into the pores of said adsorbent particles while the congealed waxy constituents remain on the surface of said particles, thereafter effecting removal of said waxy constituents from the surface of said adsorbent particles while leaving sorbed said non-congealed liquid constituents, mixing the adsorbent bearing sorbed liquid oily constituents with a sufficient amount of hot adsorbent of similar type to heat it to a temperature suitable for the conversion of said sorbed liquid oily constituents to lower boiling products, effecting substantial separation of said lower boiling products from the used adsorbent upon which a carbonaceous contaminant has been deposited, effecting removal of said contaminant from the used adsorbent and reusing at least a portion of the adsorbent after said contaminant removal as the adsorbent on which said waxy stock is coated as aforesaid.

6. The method for converting a waxy mineral oil stock into gasoline and wax products which comprises: coating the waxy mineral oil stock onto the surface of particles of solid adsorbent material of greater than about 0.01 inch average particle diameter and suitable as a hydrocarbon cracking catalyst, substantially immediately chilling the coated adsorbent to effect congealing of wax constituents in said waxy stock coated on said adsorbent particles, permitting the adsorbent particles to remain coated with said waxy stock while maintaining said waxy constituents in congealed form until substantially all of the non-congealed liquid constituents of said waxy stock are sorbed into the pores of said particles leaving the congealed waxy constituents on the surface of said particles, thereafter effecting removal of said wax constituents from the surface of said adsorbent particles while leaving the non-congealed liquid oily constituents still sorbed in the pores of said adsorbent particles, heating said adsorbent bearing sorbed liquid oily constituents to a temperature at which said liquid oily constituents are catalytically converted to lower boiling gasoline containing products, effecting substantial separation of said lower boiling products from the used adsorbent upon which a carbonaceous contaminant has been deposited as a result of the conversion of said liquid oily constituents, effecting removal of said contaminant from the used adsorbent, cooling the adsorbent and reusing it as the adsorbent upon which said waxy mineral oil stock is coated as aforesaid.

7. The method of deoiling slack wax stocks which comprises: coating said slack wax stock in liquid form onto the surface of particles of adsorbent material in an adsorbent coating zone, said adsorbent particles being of at least 0.01 inch average diameter, chilling the coated adsorbent particles to effect precipitation of wax constituents in said slack wax stock coated thereon at least within about 10 minutes of the beginning of the adsorbent coating, maintaining the wax constituents in precipitated form on said adsorbent particles for a period of at least 0.1 hour until substantially all of the non-precipitated liquid constituents of said slack wax are sorbed into the pores of said adsorbent particles leaving the precipitated wax on the surface of said particles.

effecting removal of the precipitated wax from the surface of said adsorbent particles while leaving the liquid constituents still sorbed in the pores of said adsorbent particles, separately passing the adsorbent bearing the sorbed liquid constituents through a confined conversion zone in admixture with a sufficient quantity of hot regenerated particle form adsorbent of similar type to heat it to a temperature suitable for conversion of said sorbed liquid constituents to lower boiling hydrocarbon products, separating the lower boiling products in the gaseous phase from the used adsorbent, passing the used adsorbent through a confined regeneration zone while contacting it therein with a combustion supporting gas at a controlled elevated temperature to remove contaminant deposits from the adsorbent, cooling a portion of the hot regenerated adsorbent and recycling it to said coating zone and utilizing the remainder of the hot regenerated adsorbent as the hot regenerated adsorbent which is mixed with the adsorbent bearing sorbed liquid constituents as aforesaid.

8. The cyclic process for providing deoiled wax and gasoline containing products from a wax-oil charge stock by means of a particle form catalytic adsorbent material which comprises: subjecting said wax-oil stock to an intimate contacting with the particle form adsorbent catalyst made up of particles of average diameter within the range about 0.022 inch to 0.5 inch and having a substantial catalytic activity for hydrocarbon cracking reactions under conditions of temperature wherein the waxy constituents of said stock become congealed at the latest within about 10 minutes of the beginning of said contacting, continuing said contacting until substantially all of the non-congealed liquid constituents of said stock are sorbed into the pores of said adsorbent particles while leaving the congealed wax on the surface of said particles, effecting the removal of the wax from the surface of said particles, and collecting the same as deoiled wax product, mixing the catalyst bearing sorbed oily constituents with hot catalyst of similar type to heat it to a suitable temperature for the conversion of said oily constituents to a lower boiling gasoline containing hydrocarbon product, passing the mixture through a confined conversion zone to effect the conversion of said oily constituents, effecting a separation of the lower boiling hydrocarbon products from the used catalyst bearing a contaminant deposit, passing the separated used catalyst through a confined regeneration zone while contacting it therein with a combustion supporting gas at a controlled elevated temperature to remove contaminant deposits from said catalyst, utilizing a portion of the regenerated catalyst for contacting cool catalyst bearing sorbed liquid constituents from said wax-oil stock as aforesaid and cooling the remainder of said regenerated catalyst and utilizing it for contacting said wax-oil stock as aforesaid.

9. The method for producing deoiled wax and a gasoline containing hydrocarbon product from a wax-oil petroleum charge stock which comprises: encasing particles of adsorbent catalyst having an activity for hydrocarbon cracking and having an average diameter of at least 0.01 inch in said wax-oil petroleum stock under conditions of temperature such that at least most of the wax constituents of said stock are in congealed state substantially from the beginning of the contact of the stock with the catalyst particles, maintaining said catalyst particles encased in said wax-oil

stock until substantially all the non-congealed oily constituents of said stock are sorbed into the pores of the catalyst particles leaving the wax constituents of said stock in congealed state on the surface of the catalyst particles, effecting a separation of the wax constituents of said stock from the surface of said particles and cooling the same as deoiled wax products, passing the particle form catalyst after separation from the wax constituents but still bearing the sorbed oily constituents downwardly through a confined conversion zone maintained under a temperature suitable for the cracking conversion of said oily constituents to lower boiling gasoline containing hydrocarbon products, moving said catalyst through said zone as a downwardly gravitating substantially compact column withdrawing gaseous conversion products from said conversion zone, separately withdrawing the particle form catalyst bearing a contaminant deposited during the hydrocarbon conversion from the lower section of said conversion zone, passing the used catalyst through a confined regeneration zone in contact with a combustion supporting gas to effect removal of said contaminant by burning while controlling the temperature of said catalyst above that minimum required for practical contaminant burning rates and below a temperature at which said catalyst would suffer permanent loss in catalytic activity, withdrawing the hot regenerated catalyst from the regeneration zone cooling at least a portion of said regenerated catalyst to a temperature below about 100° F. and again encasing said catalyst in said wax-oil stock as aforesaid.

10. The method for removing oily constituents from a waxy hydrocarbon stock which comprises: subjecting said waxy stock to an intimate contacting with a particle form solid adsorbent material comprising particles of at least 0.01 inch average diameter, effecting sorption of the liquid oily constituents of said waxy stock into the pores of said adsorbent particles while substantially preventing sorption of the wax constituents by maintaining the temperature during said contacting at a level at which the wax constituents become congealed, effecting the separation of the wax constituents from the surface of said adsorbent particles, passing said adsorbent particles bearing the liquid oily constituents of said waxy stock in the pores thereof during a confined conversion zone in admixture with a substantial quantity of hot particle form heat carrying material to heat it to a temperature suitable for the conversion of said sorbed oily constituents to lower boiling products, effecting the separation of said lower boiling products from the used adsorbent material, reconditioning at least a portion of said adsorbent material to put it in condition for reuse in contacting said waxy stock and then again using the reconditioned adsorbent material for contacting said waxy stock as aforesaid.

11. The method of deoiling waxy hydrocarbon stocks which comprises: coating the surface of porous solid adsorbent particles of at least 0.01 inch average diameter with said waxy stock at a temperature just slightly above that at which the waxy constituents begin to crystallize substantially immediately chilling the coated adsorbent particles to effect crystallization of the wax constituents of said stock in a coating zone, permitting said adsorbent particles to remain coated with said waxy stock until substantially all the oily constituents are sorbed into the pores of the adsorbent particles leaving the crystallized wax

15

on the surface of the particles, thereafter melting the wax from the surface of the sorbent particles and collecting the melted wax separately of the adsorbent particles and sorbed oily constituents, passing the adsorbent particles bearing the sorbed oily constituents through a confined conversion zone under temperature conditions suitable for effecting the conversion of said oily constituents to lower boiling gasoline containing hydrocarbon products, separating the gasoline containing hydrocarbon products from the used sorbent particles, reconditioning at least a portion of the used adsorbent particles and returning the reconditioned particles as the adsorbent charge to said coating zone.

12. A method for preparing deoiled wax and gasoline hydrocarbon products from wax-oil petroleum stocks which comprises: maintaining a liquid column of said wax-oil stock at a temperature slightly above that at which the waxy constituents begin to congeal, maintaining below and contiguous with the bottom of said column of wax-oil stock a column of water, maintaining a short length of the column of water immediately below the column of wax-oil stock at a temperature near that of the wax-oil stock and maintaining the remainder of said column of water at a temperature at which the waxy constituents of said stock will congeal, dropping particles of solid adsorbent having an average diameter of at least 0.01 inch and having a substantial catalyst activity for the cracking conversion of hydrocarbons downwardly through said column of wax-oil stock to cause said particles to become coated with wax-oil stock, causing the coated particles to drop downwardly into and through said column of water to cause the waxy constituents in the stock coating said particles to become congealed, removing the particles bearing the coating of wax-oil stock from said water column and permitting the particles to stand at a temperature below the congealing temperature of said waxy constituents until substantially all the non-congealed constituents of the wax-oil stock coating said particles are sorbed into the pores of said adsorbent particles while leaving the waxy constituents on the surface of said particles, then contacting the adsorbent particles with heated water to melt and to remove the waxy constituents from the surface of said particles while leaving the non-congealed constituents of the wax-oil stock sorbed in the pores of said particles, purging said adsorbent particles substantially free of water by means of a suitable purge gas, mixing said purged particles of adsorbent bearing non-congealed constituents of said wax-oil stock with a substantial quantity of hot regenerated adsorbent particles of similar type to provide a heated mixture of adsorbent at a temperature suitable for effecting the conversion of said sorbed oily constituents to lower boiling gasoline containing products, passing the mixed adsorbent with a substantial quantity of contact particles downwardly through a confined conversion zone wherein the oily constituents are converted, withdrawing the gasoline containing oily constituents in the gaseous phase from said conversion zone, separately withdrawing sorbent material bearing a carbonaceous contaminant deposited during the hydrocarbon conversion from the lower section of said conversion zone, passing the used adsorbent through a confined regeneration zone in contact with a combustion supporting gas to effect burning of the contaminant deposit, controlling the temperature of

16

said adsorbent during the regeneration below a temperature at which it would suffer permanent heat damage to its porosity and catalytic activity, returning a portion of the hot adsorbent to said conversion zone, cooling another portion of said hot regenerated adsorbent to a temperature below about 100° F., returning the cooled adsorbent to said liquid column of wax-oil stock.

13. A method for deoiling wax-oil petroleum stocks which comprises: maintaining a liquid column of said wax-oil stock at a temperature slightly above that at which the waxy constituents begin to congeal, dropping particles of solid adsorbent catalyst material of at least 0.01 inch average diameter which are suitable for effecting hydrocarbon cracking conversions and suitable for sorbing liquid oil in its pores through said column to deposit a film of said waxy stock on the surface of said catalyst particles, immediately dropping said catalyst particles into a bath of a suitable cooling liquid maintained at a temperature suitable for congealing the waxy constituents of said wax-oil stock, permitting the adsorbent particles to remain coated with said wax-oil stock while maintaining the waxy constituents in a congealed state until substantially all the non-congealed constituents are sorbed into the pores of said particles, thereafter effecting removal of the waxy constituents from the surface of said catalyst particles while leaving said non-congealed liquid constituents sorbed in the pores of said particles, passing said catalyst particles bearing sorbed liquid constituents of said wax-oil stock through a confined conversion zone while heating it to a temperature suitable for effecting conversion of said liquid constituents to lower boiling gasoline containing hydrocarbon products, separating said lower boiling products from the used catalyst, effecting the regeneration of said used catalyst at an elevated temperature by means of a combustion supporting gas, cooling at least a portion of the regeneration catalyst and returning it to said liquid column of wax-oil stock as the catalyst charge thereto.

14. The method for removing oily constituents from a waxy petroleum stock which comprises: subjecting said waxy stock to an intimate contacting with an inorganic oxide gel adsorbent consisting of particles of generally spheroidal shape and of an average diameter of at least about 0.01 inch, whereby the waxy stock is coated onto the surface of said adsorbent particles, controlling the temperature of said waxy stock so that the wax constituents become congealed at the latest substantially immediately after the waxy stock is coated upon said particles, causing the adsorbent coated with the waxy stock to stand at a temperature at which said wax constituents remain congealed until substantially all the non-congealed liquid constituents of said stock are sorbed into the pores of said particles leaving the wax on the surface thereof, then removing the wax from the surface of said adsorbent particles and collecting the removed wax separately of the adsorbent particles, mixing the adsorbent particles bearing sorbed non-congealed liquid constituents of said waxy stock with a substantial amount of hot regenerated adsorbent of similar type to heat it to a temperature suitable for effecting the conversion of said liquid constituents to lower boiling gasoline containing hydrocarbon products, passing the mixed adsorbent as a substantial compact gravitating column of particles downwardly through a confined conversion zone to effect the conversion of said liquid

constituents withdrawing the lower boiling hydrocarbon products from said conversion zone, separately withdrawing the used adsorbent bearing a carbonaceous contaminant from the lower section of said conversion zone, passing the used adsorbent through a confined regeneration zone as a substantially compact column in contact with a combustion supporting gas to burn off said contaminant while controlling the temperature of said adsorbent below a heat damaging level, withdrawing the regenerated adsorbent from the lower section of the regeneration zone, utilizing a portion of the hot regenerated adsorbent for mixing with the cooler liquid constituent bearing adsorbent as aforesaid, cooling the remainder of said hot regenerated adsorbent and again contacting it with said waxy stock as aforesaid.

15. The method for preparing gasoline containing hydrocarbon products and a deoiled wax product from a wax-oil petroleum stock which comprises: intimately contacting the wax-oil stock with a particle form solid adsorbent in which the average particle diameter is at least 0.01 inch and which has a substantial catalyst activity for hydrocarbon cracking reaction, substantially excluding the adsorption of the waxy constituents of said wax-oil stock into the pores of said adsorbent particles by maintaining said waxy constituents in congealed form while permitting the non-congealed liquid oily constituents to be adsorbed into the pores of said adsorbent, after substantially all of said liquid constituents are sorbed in the pores of said adsorbent effecting a separation of the adsorbent bearing said liquid oily constituents from said waxy constituents in a separate zone, mixing the adsorbent bearing the liquid oily constituents with a sufficient amount of hot regenerated adsorbent of similar type to heat it to a temperature suitable for effecting the catalytic cracking of said liquid oily constituents to lower boiling gasoline containing hydrocarbon products, passing the mixed adsorbent through a confined conversion zone to effect the conversion of said sorbed liquid oily constituents, separately introducing a vaporized hydrocarbon fraction into contact with said adsorbent within said conversion zone to effect the catalytic cracking conversion of said hydrocarbon fraction to gasoline containing products, effecting the separation of the mixed hydrocarbon products in the gaseous phase from the used solid adsorbent, passing the used adsorbent through a confined regeneration zone in contact with a combustion supporting gas to burn off contaminant deposited thereon during the hydrocarbon conversion, controlling the temperature of the adsorbent during the regeneration below a heat damaging level, withdrawing the regenerated adsorbent from said hot regeneration zone, utilizing the portion of hot adsorbent with the cooler liquid oily constituent bearing adsorbent as aforesaid, cooling the remainder of said hot regenerated adsorbent and again utilizing it for contacting said wax-oil stock as aforesaid.

16. The method for separating oily constituents from waxy constituents present in a waxy hydrocarbon stock which comprises: coating said

waxy stock onto the surface of particles of solid adsorbent hydrocarbon cracking catalyst of greater than about 0.01 inch average particle diameter, limiting the average thickness of the wax coating on said catalyst particles to less than about 0.1 inch, permitting the catalyst particles to remain coated with said waxy stock within the range 1 to 24 hours and maintaining the temperature of the waxy stock during said period beginning at least substantially immediately after initial contact with said catalyst at a level at which waxy constituents in said stock are congealed whereby non-congealed liquid constituents are sorbed into the pores of said catalyst particles while the congealed waxy constituents remain on the surface of said particles, thereby effecting the removal of said waxy constituents from the surface of said catalyst particles while leaving sorbed non-congealed liquid oily constituents within the pores of said particles, passing the separated catalyst particles bearing the sorbed oily constituents as a substantially compact column downwardly through a confined conversion zone in admixture with a sufficient quantity of hot regenerated catalysts of similar type to heat it to a temperature at which said liquid oily constituents are converted to a lower boiling gasoline containing hydrocarbon product, withdrawing the gasoline containing product in the gaseous phase from said conversion zone, separately withdrawing spent catalyst bearing carbonaceous contaminant deposit from the lower section of said conversion zone, passing said spent catalyst through a confined regeneration zone in contact with air to burn the carbonaceous contaminant while controlling the temperature of said catalyst below a heat damaging level, withdrawing the hot regenerated catalyst from said regeneration zone, utilizing portion of the hot regenerated catalyst for mixing with the cooler catalyst bearing said liquid oily constituents as aforesaid, cooling another portion of said hot regenerated catalyst to a temperature below about 100° F. and again coating the cooled catalyst with said waxy stock as aforesaid.
